UNITED STATES PATENT OFFICE.

NESTOR N. TOMASULO, OF PHILADELPHIA, PENNSYLVANIA, ASSIGNOR TO EVELYN JULIAN, OF PHILADELPHIA, PENNSYLVANIA.

HAIR CLIPPER.

Application filed September 30, 1925, Serial No. 59,744. Renewed March 1, 1928.

This invention relates to improvements in hair clippers, and more especially to power operated clippers having clipper elements at their opposite ends.

6 An object of the invention is to provide a suitable power operated hair clipper which will be so constructed that it will have a self-contained air chamber adjacent each clipper element, so that the movable mechanism will positively be kept cool at all times.

10 Another object of the invention is to provide a power operated hair clipper which will be provided with clipper elements at its opposite ends, and which will be adapted 15 to receive separate operating means for operating the separate clipper elements.

15 A further object of the invention is to provide a power operated hair clipper which will have its casing or housing so constructed 20 that it will readily adapt itself to practically any angle when cutting hair.

25 A still further object of the invention is to provide a power operated hair clipper which will be highly efficient in use and quite inexpensive to manufacture.

Other objects will appear as the description proceeds.

In the accompanying drawings which constitute a part of my application,

30 Figure 1 is a plan view of my hair clipper showing the interior construction thereof in dotted lines;

35 Figure 2 is a side elevation of my improved power operated hair clipper;

40 Figure 3 is a longitudinal sectional view taken on the line 3—3 of Figure 1;

45 Figure 4 is a side elevation, partly in section of the casing or housing only, with operating parts removed;

50 Figure 5 is an end elevation of the clipper casing;

55 Figure 6 is a plan view of a power operated hair clipper having a clipper element at only one end, and showing the operating mechanism in dotted lines;

60 Figure 7 is a side elevation of a single clipper element power operated hair clipper.

65 Figure 8 is a plan of a modification in which the clipping units are laterally offset from each other, and

70 Figure 9 is a side elevation of the same.

75 Like characters of reference are used through the following specification and the

accompanying drawings to designate corresponding parts.

The casing or housing 1 is provided adjacent its central portion with the reduced gripping portion 2.

80 The upper surface of the casing 1 is substantially flat, while the lower portion thereof is flat at its central portion and is provided with the concave portions 3 at either side of the central portion. Adjacent the concave portions 3 are the downwardly extending convex surfaces 4 which terminate in an upwardly direction at the outer ends of the said casing. The outer ends of said casing 1 are provided with notches 5 into which are adapted to seat the cutter bars 6 and 7 which have formed thereon coarse and fine teeth respectively. Set screws 8 are adapted to hold the cutter bars in fixed position at the ends of the casing 1.

85 Air chambers 9 are formed within the convex portions 4 of the casing 1 and are provided with the inner walls 10 which form the bottoms of the oil chambers 11, the same being formed at the opposite ends of said casing.

90 Tension posts 12 are secured at the opposite ends of the casing 1 and extend up vertically therefrom. The cutter plates 13 are adapted to seat on the cutter bars 6 and 7 and to reciprocate thereon. The said cutter plates 13 are provided with the inset bearing grooves 14 into which are adapted to be placed the substantially T-shaped outer ends of the oscillating levers 15 which are pivoted on the tensioning posts 12.

95 Bosses 16 are provided adjacent the inner ends of the clipper casing 1 and have mounted thereon the worm wheels 17, which are mounted on the stub shafts 18, the same being detachably secured in said bosses. The pins 19 are positioned in the worm-wheels 17

100 and extend upwardly therefrom and carry the slideable blocks 20, which are slideable in the longitudinally extending slots 21 in the oscillating levers 15. The upper and open sides of the oil chambers 11 are provided with the cover plates 22, which serve to retain the oil in said chambers. The cap plates 23 are adapted to extend over the tensioning screws or studs 12 and have their outer ends seated on the cutter plates 13

105 and their inner ends on the cover plates 22.

- Washers 24 are placed over the tensioning screws 12 after which the nuts 25 are tightened down on said screws until the desired tension is secured.
8. The opposite sides of the casing 1 are provided with the boxes 26 which are hollow and are adapted to receive the flexible conduits 27, the same being mounted in the bushings 28 between which are positioned the worm gears 29 which mesh with the worm-wheels 17. The reciprocating pins 30 are normally tensioned by means of the springs 31 and they are adapted to seat in the annular grooves 32 in the cables 27.
10. The worm gears 29 which mesh with the worm-wheels 17. The reciprocating pins 30 are normally tensioned by means of the springs 31 and they are adapted to seat in the annular grooves 32 in the cables 27.
15. The same construction may readily be used on a single or double ended clipper, the only difference in construction being, that in the case of the single clipper gripping extensions or holders 33 are formed on the opposite sides of the casing 1, and the flexible cable 27 enters into the casing 1 from the inner end of the said clipper. In both the single and double ended clippers air chambers are also formed at the inner end of the oil chambers as at 34. In order to close the socket or bore not in use a removable cap 35 is fitted on to the outer end of the socket.
- It has been heretofore impossible to keep the power driven hair clippers from becoming overheated due to the continual use, but I find that by providing air chambers and positioning them as I do that the clippers will not heat up even when used for a long period of time.
35. It will be understood that I do not intend to limit myself to the specific construction of the hair clippers, for it is obvious that many minor changes in detail of construction may be resorted to without departure from the spirit of the invention.
- One of my special features is the forming of longitudinally extending grooves 36 on the lower surface of the convex portions 4 of the casing 1, and registering grooves of corresponding width on the cutter bars as shown by 37.
- Having thus described my invention, what I claim as new and desire to secure by Letters Patent of the United States, is:
50. 1. A power operated hair clipper comprising a casing, a clipper element at one end, means for operating said element and an air chamber below said operating mechanism.
55. 2. A power operated hair clipper comprising a casing, clipper elements at the ends thereof, means for operating said elements and air chambers formed below and between said operating means.
60. 3. A power operated hair clipper comprising a casing, clipper elements at the ends thereof, oscillating means in said casing for operating said clipper elements, an oil chamber positioned about said operating means and air chambers below said oil chambers.
4. A power operated hair clipper comprising a casing having oil chambers formed in the opposite ends thereof, clipper elements disposed at the outer ends of said oil chambers, means in said oil chambers for operating said clipper elements and said casing being further provided with air chambers disposed below said oil chambers.
5. A power operated hair clipper comprising a casing having spaced oil chambers adjacent the opposite ends thereof, clipper elements formed at the outer ends of said oil chambers, operating means disposed within said oil chambers and separate means for connecting said operating means with an external source of power.
6. A power operated hair clipper comprising a casing having oil chambers formed at its opposite ends, clipper elements at the outer ends of said oil chambers, means in said oil chambers for operating said clipper elements and said casing being provided with spaced convex grooved portions adjacent its outer ends.
7. A power operated hair clipper comprising a casing provided with oil chambers at its opposite ends, clipper elements at the outer ends of said oil chambers, means for operating said elements, downwardly extending convex portions adjacent the ends of said casing whereby the air chambers will be formed between said oil chambers and said downwardly extending portions.
8. A power operated hair clipper comprising a casing, provided with oil chambers adjacent its opposite ends, clipper elements at the outer ends of said oil chambers, means for operating said clipper elements, means for tensioning said elements, downwardly extending convex portions formed at the opposite ends of said casing and adjacent said clipper elements, said downwardly extending portions and the lower surfaces of said clipper elements being provided with aligned parallel grooves.
9. A power operated hair clipper comprising a casing, clipper elements at the ends thereof, sockets on the outside of said casing adapted to receive the end of a flexible shaft in opposite directions means within the casing and extending into the sockets for operating said clipper elements.
10. A power operated hair clipper comprising a casing, clipper elements at the ends thereof, sockets on opposite sides of the casing adapted to receive the end of a flexible shaft in opposite directions, means within the casing and extending into the sockets for operating said clipper elements.
11. A power operated hair clipper comprising a casing, an oil chamber within the casing, a clipper element mounted angularly at the end of the casing, operating means within the casing and engaging said clipper element for operating the same, an air chamber disposed below said oil chamber.

ber to the rear of said clipper element and below the operating means, the outer surface of said chamber being flush with the outer surface of said clipper element.

5 12. A power operated hair clipper comprising a casing, an oil chamber within the casing, a clipper element mounted angularly at one end of the casing, operating means within the oil chamber in engagement with the clipper element for operating the same, an air chamber below said oil chamber and to the rear of the clipper element, the outer surface of said air chamber being flush with the outer surface of said clipper element.

10 13. A power operated hair clipper, a casing, clipper elements mounted angularly at the opposite ends thereof, operating mechanisms in the casing and engaging the clipper elements respectively for operating the

20 same, convex depending portions below said operating mechanisms and to the rear of the clipper elements cap mounted above the casing wall at the ends thereof, said casing between said depending portions and 25 caps being thereby reduced and forming a handle for the clipper.

14. A hair clipper comprising a casing cutter elements at the end of the casing, operating mechanism within the casing, 30 said mechanism being in operative connec-

tion with one of the cutting elements a spaced wall on the casing located below the operating mechanism and immediately to the rear of the cutting elements and extending longitudinally of the device whereby a heat radiating surface of large area is produced immediately below the operating mechanism.

15. A hair clipper comprising a casing, cutting elements at one end of the casing, operating mechanism within said casing connected operatively with one of said cutting elements, a spaced wall on said casing and projecting backwardly from a position adjacent the rear of the cutting elements and immediately below the operating mechanism, 45 whereby a heat radiating surface of large area immediately below the operating mechanism is formed.

16. A hair clipper comprising a casing, cutting elements at one end of the casing, 50 operating mechanism within the casing and operatively connected with one of said clipper elements, a spaced wall on said casing extending forwardly from a position below the operating mechanism to a position adjacent the rear of the cutting elements, whereby a heat radiating surface of large area is formed.

NESTOR N. TOMASULO.
